UNITED STATES PATENT OFFICE.

STACY B. HASELTINE, OF CHICAGO, ILLINOIS, ASSIGNOR TO WILLIAM H. MINEE, OF CHAZY, NEW YORK.

YOKE.

1,242,801.

Specification of Letters Patent. Patented Oct. 9, 1917.

Application filed April 13, 1916, Serial No. 90,840. Renewed August 27, 1917. Serial No. 188,497.

To all whom it may concern:

Be it known that I, STACY B. HASELTINE, a citizen of the United States, residing at Chicago, in the county of Cook and State of Illinois, have invented a certain new and useful Improvement in Yokes, of which the following is a full, clear, concise, and exact description; reference being had to the accompanying drawings, forming a part of this specification.

This invention relates to improvements in yokes.

For several years past, the railroads have been desirous of obtaining a draw-bar and yoke connection which will avoid slotting of the sills and at the same time be readily detachable. Furthermore, the railroads are demanding a yoke connection of the above character which is adapted to all types of standard draw-bars whether the latter have coupler key slots or not. A further requisite demanded by the railroads is a detachable draw-bar and yoke connection so arranged that all the parts are easily accessible and wherein the draw-bar may be removed or replaced without disturbing the gear proper.

The object of my invention is to provide a yoke for railway draft riggings of simple construction and which will embody all the advantageous features above indicated.

In the drawing forming a part of this specification, Figure 1 is a part side elevation, part vertical longitudinal section of a yoke showing my improvements in connection therewith. Fig. 2 is a horizontal sectional view of the structure illustrated in Fig. 1 and taken on the line 2—2 thereof. Fig. 3 is a front end elevation of the yoke. And Fig. 4 is a detail perspective of one of the locking blocks employed.

Referring to said drawing, 10 denotes a standard draw-bar having the usual butt 11 provided with upper shoulder 12 and lower shoulder 13. The yoke A, which as shown is preferably a steel casting, is provided with upper arm 14, lower arm 15, rear connecting piece 16, and a hollow, boxlike hood or head 17 at its front end, the hood being open at the front and provided with side walls 18—18, and upper wall 19, the upper wall 19 being provided on its inner face with an integral, transversely extending gib or shoulder 20, the latter being adapted to

cooperate with the upper shoulder 12 of the draw-bar. Within the yoke a shock absorbing member is illustrated conventionally by dotted lines, the shock absorber shown in the drawing being a well known type of friction gear.

The lower wall 21 of the hood is offset downwardly from the lower arm 15 a distance corresponding substantially to the depth of the shoulder or gib 20 so that when the draw-bar is inserted it may ride over the upper face of the bottom wall 21 and clear the shoulder 20.

To hold the draw-bar in proper position and lock it, I have provided a flat filler block 22 which is insertible within the hood from the front thereof, and a vertically extending block 23 which is insertible and removable vertically through a slot 24 formed in the front thickened end of the lower wall 21. The block 23 extends up within the hood sufficiently to engage the lower shoulder 13 of the draw-bar and is held in operative position by any suitable means such as a bolt 25. In order to properly brace the block 23, the inner faces of the side walls 18—18 are provided with integral shoulders or abutments 26 near the lower portions thereof, sufficient clearance being left between said shoulders 26 to permit the insertion and withdrawal of the coupler butt.

The parts are shown in assembled relation and in order to remove the draw-bar, it is apparent that the bolt 25 will first be removed, then the block 23 withdrawn from the underside of the yoke, the filler block 22 is then removed and in order to facilitate this latter operation, the bottom wall of the hood is slotted as indicated at 27 through which may be inserted any suitable tool to engage the recess 28 in the bottom face of the block 22. As will be understood, the parts are assembled in the reverse manner of that just described.

In order to provide for radial movement of the draw-bar relative to the yoke, the upper shoulder or gib 20 is provided on its inner face with a convex surface 29 and the upper portion of the block 23 is provided with a similar convexly curved face 30. In this way, the draw-bar is permitted to swing radially, it being understood that sufficient clearance is provided between the sides of the butt and the side walls of the

yoke. Furthermore, the arrangement is such that the draw-bar may move inwardly independently of the yoke.

Although I have herein shown and described what I now consider the preferred means of carrying out my invention, the same is merely illustrative and I contemplate all changes and modifications that come within the scope of the claims appended hereto.

I claim.

1. A yoke provided with a hooded forward end within which is adapted to be received a shouldered draw-bar butt, said yoke being provided with means arranged to engage the upper shoulder of a draw-bar butt, and devices, coöperable with the lower shoulder of a draw-bar butt, for detachably locking the yoke to a draw-bar, said devices including a block removable vertically from the underside of the yoke and engageable with the lower shoulder of a draw-bar and a filler block adapted to be seated beneath the butt of a draw-bar and removable from the front end of the yoke.

2. A yoke provided with a hooded forward end within which is adapted to be received a shouldered draw-bar butt, said yoke being provided with means arranged to engage the upper shoulder of a draw-bar butt, and devices, coöperable with the lower shoulder of a draw-bar butt, for detachably locking the yoke to a draw-bar, said devices including two blocks one of which is removable through the under side of the yoke and the other from the front end of the yoke.

3. A yoke provided with a hooded forward end within which is adapted to be received a shouldered draw-bar butt, said yoke being provided with means arranged to engage the upper shoulder of a draw-bar butt, and devices, coöperable with the lower shoulder of a draw-bar butt, for detachably locking the yoke to a draw-bar, said devices

including a block removable vertically from the underside of the yoke and engageable with the lower shoulder of a draw-bar and a filler block adapted to be seated beneath the butt of a draw-bar and removable from the front end of the yoke, the lower wall of said hooded end being recessed to permit access to the filler block when removing the latter.

4. A yoke provided with a hooded forward end within which is adapted to be received a shouldered draw-bar butt, said yoke being provided with means arranged to engage the upper shoulder of a draw-bar butt, and devices, coöperable with the lower shoulder of a draw-bar butt, for detachably locking the yoke to a draw-bar, said devices including two blocks one of which is removable through the under side of the yoke and the other from the front end of the yoke, the side walls of said hooded end being shouldered in front of the block which is removable from the under side, said shoulders being located to overlie the lower shoulder of a draw-bar butt.

5. A yoke of the character described having a hooded forward end provided with an integral shoulder across the top thereof, the lower wall of said hooded end being downwardly offset from the lower arm of the yoke, a filler block insertible within the hood from the front end thereof and on which a draw-bar butt is adapted to rest and be supported, a vertically extending block extending through a vertical recess in the lower wall of the hooded end, the inner faces of the side walls of the hood being shouldered to thereby back said block, and detachable means for supporting said vertically extending block in position.

In witness that I claim the foregoing I have hereunto subscribed my name this 15th day of March, 1916.

STACY B. HASELTINE.
